DESIGN FOR AN ANTISIPHONING TRAP FOR PLUMBING FIXTURES

Isaac B. Ritter, Philadelphia, Pa., assignor of
one-half to Frank T. Ray, Philadelphia, Pa.

Application September 24, 1937, Serial No. 71,776

Term of patent 14 years

To all whom it may concern:

Be it known that I, Isaac B. Ritter, a citizen of the United States, residing at Philadelphia, in the county of Philadelphia and State of Pennsylvania, have invented a new, original, and ornamental Design for an Anti-Siphoning Trap for Plumbing Fixtures, of which the following is a specification, reference being had to the accompanying drawing, forming part thereof.

Fig. 1 is a side elevational view of an anti-siphoning trap for plumbing fixtures, showing my new design;

Fig. 2 is a side elevation looking in the opposite direction to that of Fig. 1;

Fig. 3 is a plan view of the anti-siphoning trap for plumbing fixtures;

Fig. 4 is an end view of the anti-siphoning trap for plumbing fixtures; and

Fig. 5 is an end view looking in a direction opposite to that of Fig. 4.

I claim:

The ornamental design for an anti-siphoning trap for plumbing fixtures as shown.

ISAAC B. RITTER.
